ICE GRIPPER

Albert R. Bailey, 5560 Pershing Ave., St. Louis, Mo.

Filed Feb. 12, 1960, Ser. No. 8,335

3 Claims. (Cl. 36—62)

This invention relates to improvements in ice grippers and in particular is concerned with an ice gripper attachment for shoes that through a special rigid hook arrangement an elastic band can be hooked onto the bottom of shoes in a very simple manner.

Ice grippers and other anti-skid shoe attachments have been used in the past for the purpose of preventing skidding upon ice or other slippery surfaces. These attachments, although successful, for their stated purpose initially, have been largely objectionable because of a tendency to work out of adjustment upon the shoe. Such attachments have also been objectionable because of the length of time required to fasten them to the shoe. An illustration of such a gripper is shown in Smith Patent No. 2,401,891, which uses a single securing strap fitting under a depressed central portion of the ice creeper. Such an ice gripper is difficult to secure and once secured to the shoe, is prone to slippage.

By means of the instant invention, there has been provided an ice gripper which has a rigid hook that serves to secure an elastic band. The elastic band can be fitted over the shoe and then hooked in underneath the rigid hook in a matter of seconds. The band, by virtue of its looped construction has two areas of friction or engagement on the top surface of the shoe, and serves to hold the gripper in place.

The ice gripper can be made very simply from a shaped steel plate and can be adjusted in a matter of seconds. The readily securable features of the plate tend to dispel the natural resistance of many people to the use of the ice gripper and thereby serves an added advantage in having people use the gripper that otherwise would not. The gripper is also extremely simple to secure and can be used without any requirement of manual dexterity at all.

It is accordingly an object of this invention to provide an ice gripper attachment which can be made of plate material having a rigid hook at one side to which an elastic loop can be hooked over the top of a shoe.

It is another object of this invention to provide an ice gripper attachment made of steel plate having a vertical hook at one side with an adjustable loop extending from the other side that can be hooked over the shoe and underneath the hook to hold the gripper to the shoe in binding relation.

Yet a further object of this invention is to provide an ice gripper attachment for shoes having a hook to which an elastic loop can be secured, in which the loop may be adjusted by moving it through securing slots in the steel plate.

Still a further object of this invention is to provide an ice gripper attachment that can be made simply and economically from a single piece of shaped steel plate with a strong elastic band, which can be simply and expeditiously used by the wearer. Further objects of this invention will appear in the detailed description which follows and will be further apparent to those skilled in the art.

2

For the purpose of illustration, there is shown in the accompanying drawing a preferred embodiment of this invention. It is to be understood that this drawing is for the purpose of example only and that the invention is not limited thereto.

In the drawings:

Figure 1 is a top plan view of the ice gripper;
Figure 2 is a view in front elevation of the ice gripper
at Figure 1;

10 Figure 3 is a bottom plan view of the ice gripper of
Figure 1;

Figure 4 is an enlarged view in section taken on the
line 4—4 of Figure 1 showing the manner of adjustably
securing the end of the rubber band to the ice gripper;
15 and

Figure 5 is a pictorial view of the ice gripper attached
to the left shoe of a wearer.

As shown in the drawings, the ice gripper comprises
an ice gripper plate generally indicated by the reference
20 number 10 and an elastic retaining band 12. The plate
is made of flat steel plate or other rigid material of con-
struction which can be appropriately shaped. As shown
in Figure 1, the ice gripper plate 10 has a flat base por-
25 tion 14 having band securing extensions 16 and 20 at
opposite sides.

The ice gripping feature of the ice gripper plate is pro-
vided by four triangular shaped teeth elements 22, which
are struck out from around the sides of the plate. These
30 teeth, by virtue of their arrangement, provide both sta-
bility and a means for gripping any slippery surface, such
as ice, to give a good anchoring engagement.

A hook member 24 is provided at one side between
the band retaining extensions of the ice gripper plate.
The hook member 24 is formed of a substantially verti-
35 cal shank portion 26 and a terminal hook member 28.
It will be noted that the shank slants upwardly and verti-
cally away from the ice gripper plate which provides a
wedging action when the band is hooked around it to
firmly engage the shoe with the ice gripper plate.

40 The previously mentioned band retaining extensions 16
and 20 are alike in every detail and only the element 16
need be described. This element comprises an extension
of the base plate 14. The extension has three slots pro-
vided in it, namely slots 30, 32 and 34. Each of these
45 slots has a length just slightly greater than the width of
the band 12 as is shown in Figure 1 and a width just
slightly greater than the thickness of the band. Thus by
threading the terminal end of the band through these
50 slots, as shown in Figure 4, the band may be frictionally
engaged and locked in the band retaining extensions. It
will be obvious that the adjustment of length of the band
may be simply effected by properly manipulating the end
of the band and threading the band through the slots 30,
55 32 and 34, to either lengthen or shorten the loop.

Use

56 The ice gripper plate is adapted to be attached to a
shoe in a matter of seconds. The attachment can be
57 effected very simply and expeditiously without any com-
plicated fastening movements required. This, of course,
is both an advantage in securing the ice gripper and also
in taking it off, since numbed fingers can reduce the
60 dexterity of the operator to a point where attachment or
disengagement of straps using buckles and the like can-
not be effected.

61 The use of the ice gripper plate is best shown in
Figure 5 where an ice gripper plate is shown attached to
65 a left shoe of the user. It will be noted that the securing
hook 24 is placed at the left edge of the shoe sole with
the plate being placed at the bottom of a shoe, with one
70 edge of the plate abutting against a heel 40 of the shoe,
generally indicated in dotted lines by the numeral 42. In

the position shown in Figure 5, the band 12 will initially extend to the right side of a shoe and then is simply stretched over the shoe and hooked under the terminal hook member 28, in the manner shown. The whole operation takes place in only a matter of seconds and requires no complicated manipulation and should be completely self-evident.

It will be noted that in the attachment of the ice gripper plate to the shoe, as shown in Figure 5, that there are, in effect, two strands formed by the band 12. These strands 44 and 46 hug the shoe tightly under elastic tension and, because of their separation, very effectively bind the plate to the bottom of the shoe. In addition, because of the separation of the strands 44 and 46, the entire looped band 12 does not tend to work down or off the shoe out of engagement. Thus, a very effective, tight gripping gripper plate which can be attached in a very minimal amount of time has been provided by this invention.

It will be evident that the gripper plate can be attached to the right shoe in just the reverse manner as described above. Thus, the hook portion is placed at the right side of the sole of the shoe and the attachment is carried out in the manner previously described for the left hand shoe.

In use, the ice gripper works actually as a two prong gripper that grips the ice during the first stroke of a natural walking motion of the foot. The two rear prongs act mainly for reversible purposes to enable the gripper to be used as right or left shoe grippers. The width of the gripper from front to rear is for the proper positioning and holding between the heel and point of contact.

In operation the strap or band being doubled by its engagement with the hook and by its proper spacing through the strands 44 and 46 as shown in Figure 5, acts not only as a fastener to the connecting hook, but also fits the top of the shoe quite comfortably and prevents any uncomfortable cutting into the top surface of the foot. Additionally, the strap is prevented from rolling down out of place and keeps the gripper in position under the foot as it fits at the narrowest part of the shoe arch and, as a result, the gripper cannot move forward. The two teeth at the front normally engage the slippery surface to a much greater extent than the rear teeth because of the slanting construction of the shoe between the ball of the foot and the heel and the arch area. As a result, the ice gripper has aainless pivoting action and cannot move backwards as the width of the plate is sufficiently wide to bear against the heel of the shoe which makes a natural stop for the gripper plate.

When used on ladies' shoes the ice gripper plate must naturally be smaller, and due to the extreme variation of shoe heels and styles, it can be used quite satisfactorily under the ball of the foot. Thus the strap design allows the gripper to be fitted on each side of the widest part of a lady's shoe thus keeping it in proper place and retaining the quick on and off features of the gripper.

Various changes and modifications may be made within this invention as will be apparent to those skilled in the art. Such changes and modifications are within the scope and teaching of this invention as defined by the claims appended hereto.

What is claimed is:

1. An anti-slip device for attachment to the bottom of a shoe which comprises a rigid, flat plate having gripping elements on its bottom surface, a rigid hook extending vertically from one side of the plate, an elastic band anchored at its ends to said plate and forming a loop extending from an opposite side of the plate, said looped band being adapted to be stretched over the shoe to engage said hook at a medial portion of the loop and thereby define two separated elastic strands extending over the shoe from one side of the plate to the other and retain the plate on the bottom of the shoe, and means for adjusting the length of said looped band, said means comprising a series of slots at one side of the plate through which the end of the band is threaded, said slots being only slightly larger than the band whereby the band is locked in the slots when under tension but may be threaded through the slots when tension is released.
2. An anti-slip device for attachment to the bottom of a shoe which comprises a rigid flat plate having gripping elements on its bottom surface, a rigid hook extending vertically from one side of the plate and diverging away from said plate and downwardly, an elastic band anchored at its ends to said plate and forming a loop extending from an opposite side of the plate, said looped band being adapted to be stretched over the shoe to engage said hook at a medial portion of the loop and thereby define two separated elastic strands extending over the shoe from one side of the plate to the other and retain the plate on the bottom of the shoe.
3. An anti-slip device for attachment to the bottom of a shoe which comprises a rigid flat plate having gripping elements on its bottom surface, a rigid hook extending vertically from one side of the plate and diverging away from said plate, the hook opening away from said plate and downwardly, an elastic band anchored at its ends to said plate and forming a loop extending from an opposite side of the plate, said looped band being adapted to be stretched over the shoe to engage said hook at a medial portion of the loop and thereby define two separated elastic strands extending over the shoe from one side of the plate to the other and retain the plate on the bottom of the shoe, and means for adjusting the length of said looped band, said means comprising a series of slots at one side of the plate through which the end of the band is threaded, said slots being only slightly larger than the band whereby the band is locked in the slots when under tension but may be threaded through the slots when tension is released.
